UNITED STATES PATENT OFFICE.

ADOLF BLEICHERT, OF GOHLIS, SAXONY, GERMANY, ASSIGNOR TO ADOLF BLEICHERT & CO., OF SAME PLACE.

RAIL FOR ELEVATED WIRE-ROPE LINES.

SPECIFICATION forming part of Letters Patent No. 380,984, dated April 10, 1888.

Application filed January 12, 1888. Serial No. 260,552. (No model.) Patented in Belgium April 4, 1887, No 76,968, and in Austria-Hungary August 16, 1887, No. 13,829 and No. 34,432

To all whom it may concern:

Be it known that I, ADOLF BLEICHERT, a citizen of Germany, residing at Gohlis, in the Kingdom of Saxony, Germany, have invented 5 certain new and useful Improvements in Rails for Elevated Wire-Rope Lines, (for which I have received the following patents: in Belgium, No. 76,968, April 4, 1887, and Austria-Hungary No. 13,829 and No. 34,432, August 16, 10 1887;) and I do hereby declare the following to be a full, clear, and exact description of the invention, such as will enable others skilled in the art to which it appertains to make and use the same.

15 This invention relates to a rail or track for the suspended cars of elevated wire-rope lines to run on.

This invention consists in the novel construction and combination of the rail and its 20 supports, as hereinafter fully described and claimed.

In the drawings, Figure 1 is a side view of a portion of an elevated wire-rope railway. Fig. 2 is a side view of a portion of the rail. 25 Figs. 3, 4, and 5 are cross-sections through the rail and its junction-plates. Figs. 6, 7, and 8 show the connection of the end of a rail to a fixed support or anchorage, and are respectively a side, a plan, and an end view, partly 30 in section. Figs. 9, 10, and 11 are respectively a side view, a plan view, and a cross-section through the rail, showing its connection to an anchor-chain. Fig. 12 is a detail side view, partly in section, of the rail and the top portion of one of its intermediate 35 supports. Figs. 13 and 14 are cross-sections through the rail and the top portion of the support, of which Fig. 14 also shows the bracket which prevents the rail from turning.

40 A is the rail having spherical-faced upper and lower flanges, *a*, and an intermediate vertical web, *a'*.

B are the junction-plates having spherical outer surfaces, *b*. These plates fit in close to 45 the web of the rail and form with it a complete circle in cross-section. This circular cross-section may be slightly elongated and made oval or egg-shaped, if desired; but it must be made so as to permit the car-wheels 50 to run upon it.

C are the countersunk headed rivets which unite the rails and their junction-plates.

If desired, the rail may be formed in two parts, as shown in Figs. 4 and 5, and provided with the interlocking shoulders *c* and united 55 by rivets *c'*. This form of rail will be found to possess all the advantages of a round rail in cheapness and durability, and its sections are more easily coupled together than long solid bars, which often break where welded up. 60

D is a fixed support or anchorage for the end of the rail, which has two junction-plates, B, riveted to it.

E is a key which passes through a slot in the end of the said rail and the plates B, and 65 which rests in the notch *d'* of the plate *d*, which bears against the said fixed support.

F is a tubular connection having an eye, *f*, for fastening onto the anchor-chain *f'*. The rail is placed inside the connection, and the 70 key is passed through it and through the rail.

G are the vertical intermediate supports for the rail, having the brackets *H* secured at the top of them by bolts *g*. The brackets *H* are provided with concave bearings *h* for the rail 75 to rest upon, and are also curved convexly in their longitudinal direction, so as to set up the rail slightly and make it bear hardest over the center of the support.

I is a bracket secured at intervals on the 80 line to the brackets *H*, and provided with the projecting flange *h'*, which bears against the vertical web of the rail and prevents it from turning upon its longitudinal axis.

What I claim is—

1. A rail for elevated wire-rope lines, provided with spherical-faced flanges united by a vertical web, in combination with junction-plates having spherical outer surfaces and countersunk rivets uniting said rail and plates 90 so that their cross-section is substantially circular, as set forth.

2. A rail for elevated wire-rope lines, formed in two parts, riveted together, and provided with interlocking shoulders, and with spherical-faced flanges, in combination with junction-plates having spherical outer surfaces and countersunk rivets uniting said rail and plates 95 so that their cross-section is substantially circular, as set forth.

3. The combination, with the rail A, having spherical-faced flanges *a*, the plates B, and the countersunk rivets fastening said plates and rail together, of the key E, passing through 5 the end of said plates and rail for anchoring the end of the rail, substantially as set forth.
4. The combination, with the rail A, of the bracket secured to the top of the intermediate support, said bracket being curved convexly 10 in its longitudinal direction and provided with

a concave seat for the rail, and the bracket I, secured to the support-bracket and provided with the flange *h* to prevent the rail from turning, substantially as set forth.

In testimony whereof I affix my signature in 15 presence of two witnesses.

ADOLF BLEICHERT.
